Primary Examiner — Samantha Wood

Assistant Examiner — Emily A Caven

(57) CLAIM

The ornamental design for an animal treadmill, as shown and described.

DESCRIPTION

1. Animal treadmill

1.1 : Front

1.2 : Back

1.3 : Left

1.4 : Right

1.5 : Top

1.6 : Bottom

1.7 : Perspective view 1

1.8 : Perspective view 2

The product incorporating the design is used for animals to walk and run for exercise; The essential features of the design are it's shape; The drawing or photograph which can best show the essential features of the design is perspective view 1; The solid lines in the figures show portions of the animal treadmill that form part of the claimed design, and the dashed broken lines in the figures show portions of the animal treadmill that form no part of the claimed design.

1 Claim, 8 Drawing Sheets
